UNITED STATES PATENT OFFICE.

ALBERT H. STEBBINS, OF LOS ANGELES, CALIFORNIA.

TABLE CONCENTRATOR.

Application filed April 12, 1922. Serial No. 551,935.

To all whom it may concern:

Be it known that I, ALBERT H. STEBBINS, a citizen of the United States, residing at Los Angeles, in the county of Los Angeles and State of California, have invented an Improvement in Table Concentrators, of which the following description, in connection with the accompanying drawings, is a specification, like characters on the drawings representing like parts.

This invention relates to concentrators of the table type for the separation of ores and other materials in accordance with their differences in specific gravity.

Most metals or values have a higher specific gravity than the accompanying impurities, and the values are commonly distributed throughout a relatively large amount of impurities or foreign matter so that it is usually necessary to treat a large amount of material as compared with the amount of values obtained therefrom.

The ores to be treated may vary in size from a fine pulverized material to large lumps or rocks, and in ore treating mills the ore is commonly brought to the mill in cars and is discharged therefrom upon a series of strong inclined bars supported in spaced relation to form what is known as a grizzly.

The finer materials pass between the bars of the grizzly while the rocks and large lumps pass over the surface of the grizzly and are delivered to a crusher. The materials reduced by the crusher and those which pass through the grizzly are delivered to a screen, and such materials as pass through the screen may be subjected to the first concentration treatment while the larger particles are recrushed.

It is desirable to remove the concentrates or values in as large lumps or particles as is practical, because in each crushing operation some values may be reduced to such a fine state that they cannot be recovered. The materials therefore are commonly subjected to the first concentration treatment while the particles are relatively large in size that some of the values or concentrates may be removed at this stage. Other values may not be released from the larger lumps of foreign matter at this stage and these lumps are therefore recrushed to release the values they contain, after which they are subjected to a second concentration operation. The

materials may be successively crushed, screened and treated by concentrators to remove at different stages the values released as the materials are reduced in size, and the tailings that are separated from the values in each concentrating operation may be subjected to further treatment.

The concentrator of the present invention is designed more particularly to concentrate the materials at one or more of the stages of ore treatment above mentioned, and the present concentrator is provided with a deck having riffles arranged thereupon so that as the materials pass along the deck the concentrates or values will be deflected in one direction by the riffles while the lighter particles or tailings will move in a different direction.

Movement of the materials over the deck surface may be produced by movement imparted to the deck; by sloping the deck; and by the use of air. In the embodiment of the invention illustrated the materials are advanced longitudinally of the deck by a back and forth movement imparted thereto, and their advancement along the deck is facilitated by the passage of air upwardly through the deck and materials. The passage of air upwardly through the materials serves also to promote stratification of the materials, as the lighter particles are lifted by the air while the heavier particles work downward.

As the materials travel along the deck of the present invention a general or preliminary stratification is quickly accomplished by the air, and this causes the lighter particles or tailings to rise sufficiently to pass over the riffles upon the deck, while the heavier particles will fail to clear these riffles. Movement of the lighter materials transversely of the deck is produced by inclining the deck transversely and this causes the lighter particles to move toward the lower side of the deck while the heavier particles or concentrates are prevented by the riffles from moving similarly.

Having the above matter in mind, important features of the present invention reside in an improved deck construction; in the disposition of the riffles relative to the direction in which the materials are advanced along the deck; in novel means for actuating the deck to advance materials along the same; in a novel construction for

delivering air to the apertures of the deck and for removing air from above the deck; and in adjustable means for directing the materials discharged from an end of the deck into different receptacles.

Other features of the invention and novel combination of parts in addition to the above will be hereinafter described in connection with the accompanying drawings, which illustrate one good practical form thereof.

In the drawings:

Fig. 1 is a side elevation of a concentrator constructed in accordance with the present invention, a part of the deck cover being broken away;

Fig. 2 is an enlarged perspective view of receptacles mounted at the delivery end of the deck;

Fig. 3 is a sectional view taken on the line 20 3—3 of Fig. 1;

Fig. 4 is an enlarged sectional view through a casing containing mechanism for imparting movement to the deck;

Fig. 5 is a sectional view of Fig. 4 showing the casing cut upon the line 5—5;

Fig. 6 is a perspective view of a rocking frame to be described;

Fig. 7 is a perspective view of a portion of the deck;

Fig. 8 is a plan view of the deck supporting casing, the cover and deck surface being removed;

Fig. 9 is a side elevation of Fig. 8;

Fig. 10 is an enlarged transverse sectional view through the deck casing of Fig. 8;

Fig. 11 is a plan view of the deck supporting carriage;

Fig. 12 is a plan view of the deck with the cover removed;

Fig. 13 is a view similar to Fig. 12 but shows the feed hopper in a different position; and

Fig. 14 is an enlarged longitudinal sectional view through one of the surface channels of which the deck surface is formed.

In the drawings, the concentrator table is shown as consisting of a supporting frame 10 having a carriage 11 movably supported thereupon, and upon the carriage 11 is mounted the deck casing 12 having the cover 13.

The supporting frame 10 may be constructed of upper and lower angle beams 14 and 15 connected by angle irons as shown to form a rectangular frame of hollow construction. The carriage 11 may be variously mounted upon the frame 10, and in the construction shown, rocking frames 16 and 17 are provided, pivoted intermediate their ends to the frame 10 and connected at their upper ends to the carriage 11. The frame 16 has a downwardly extending central lever 18, and short levers 19 upon each side thereof. These levers have shafts 20, 21 and 22 extending through them and rigidly secured

thereto to form a rigid rocking frame, and the ends of the shaft 20 are mounted in bearings 23 secured to the carriage 11 while the ends of the shaft 21 are mounted in bearings 24 secured to the beams 14 of the supporting frame. Each of the side levers 19 has an arm 25 extending laterally therefrom for a purpose to be described.

In the construction shown the table actuating means, to be described, is connected to 75 but one of the rocking frames, namely the frame 16, and this frame is therefore provided with the central lever 18 which is omitted from the other rocking frame 17. The frame 17 may consist of side levers 26 80 and 27 rigidly connected by cross bars 28 and 29, and having the shafts 30 and 31 extending therethrough. The ends of the shaft 30 are mounted in bearings 32 upon the frame 10 and the ends of shaft 31 are 85 mounted in the bearings 33 secured to the carriage 11.

The carriage 11 may have the configuration shown in Fig. 11 and may be constructed of angle irons consisting of side angle beams 34 connected by transverse angle bars 35, and a beam 36 is secured to the frame to extend from one side beam 34 in an inclined direction toward the other side beam as shown. The side beam 34 opposite the inclined beam 36 has a plurality of hinges 37 secured thereto to adjustably connect one side of the deck casing 12 to the carriage so that the deck casing may be adjusted transversely to different angles relative to the carriage 11.

The deck casing 12 preferably has an elongated construction and tapers in width from one end toward the other as best shown in Fig. 8. The casing 12 has a hollow construction and is formed of a number of transversely extending frames 38 each having the configuration shown in Fig. 10, and these frames 38 are secured in spaced relation transversely of the casing by the longitudinally extending angle beams 39. Each frame 38 may consist of a lower bar 40 having side bars 41 extending upwardly from the ends thereof, and the upper ends of the side bars 41 may be bent inwardly as at 110

42. Above the lower bars 40 of the deck are provided the channel or bridge bars 43 extending from one side of the deck to the other. These bars 43 serve to support the deck surface, and a comparatively large air chamber is provided below the deck surface throughout its length. To this end the deck casing 12 has a sheet metal floor 44 extending lengthwise thereof over the lower bars 40 and has sheet metal sides 45 secured to the 115 side bars 41.

It may be desirable to support the deck casing 12 at different transverse angles upon the carriage 11, and to this end, the lower side of the deck casing is secured to the 120

90

130

carriage by the hinges 37, and the upper side of the deck casing is supported in spaced relation to the carriage by the threaded rods 46. The upper ends of the rods 46 may be bent as shown in Fig. 3 to extend through ears 47 upon the casing 12 and the threaded portions of these rods extend through apertures 47 in the beam 36 and in ears 48. Nuts 49 and 50 upon the rods 46 serve to raise or lower the upper side of the deck frame.

The deck should serve to separate the light materials from the heavy materials and to impart a different movement to the heavy materials or values from that which is imparted to the light materials or tailings. In the present construction the deck surface is formed entirely of relatively small surface channels 51 which are substantially U-shaped in cross-section and are secured side by side to the channel bars 43 as best shown in Figs. 7 and 14. The surface channels 51 may be formed of sheet metal having the sides bent up so that the individual surface channels are trough-shaped, and the upstanding sides of adjacent surface channels 51 form the riffles 52. Each channel is provided with apertures 53 for the passage of air upwardly therethrough, and the apertures have upwardly inclined lips 54 formed by bending the metal at one side of an aperture upwardly to vary the size of the aperture and to direct the air passing therethrough.

The channels 51 preferably are arranged diagonally of the deck casing and their ends terminate adjacent the upper side of the casing as best shown in Fig. 12. The materials to be treated are delivered to the deck at one end thereof and advance toward the opposite end of the deck, and the deck is preferably wider at its receiving end than at the delivery end as shown, so that the materials may rapidly spread out over the deck at the receiving end thereof. The materials are conveniently delivered to the deck by a hopper 55 which may be secured at one side of the deck as in Fig. 12, or at an end thereof as in Fig. 13, in either case the hopper may have an adjustable gate 56 for controlling the flow of materials therefrom.

It is desirable to establish a substantially uniform air pressure below the entire deck surface so that the air currents passing through the aperture 53 of different surface channels will have practically the same force. To this end a wide hood 57 (see Fig. 1) is provided at the receiving end of the deck casing to deliver air to the chamber below the deck. The air may be supplied to the hood 57 under pressure by a fan 58 mounted upon the supporting frame 10, and since the deck casing 12 moves relatively to the frame 10 a flexible connection 59 is provided between the fan and hood 57.

Partitions 60 preferably are provided within the air chamber extending lengthwise thereof to prevent air from flowing laterally from one side of the chamber to the other, and these partitions serve also to support 70 the transverse channel bars 43.

The cover 13 preferably extends over the entire deck and serves to prevent the escape of dust from the machine. It is supported in spaced relation to the deck by the upright bars 41 and has downwardly extending sides 61. The upper side of the deck casing has a wall 62 extending up under the cover, and the lower side of this casing has a wall 63 extending from one end thereof to the point where the riffles commence. The air under the cover 13 preferably is removed by suction means, and to this end a hood 64 is formed upon the cover and has a conduit 65 that may be connected to a suction fan or other exhaust means. Slots 66 preferably are formed through the cover and lead into the hood, the construction being such that the air is drawn substantially uniformly from above different parts of the 90 deck.

As stated, it is desirable to impart movement to the deck which will serve to advance the materials longitudinally thereof. This may be accomplished by various means, 95 and in the construction shown, mechanism is provided for positively moving the rocking frame 16 and deck in one direction and then yieldingly moving them in the opposite direction. The movement provided in 100 the present case serves to impart an accelerated movement to the deck in one direction and to reverse quickly the direction in which the deck moves so that the momentum imparted to the materials upon the deck will cause them to slide along its surface each time the direction of movement of the deck is reversed quickly.

In the construction shown the central lever 18 of the rocking frame 16 has one 110 end of a link 67 secured thereto by a pin 68 and the opposite end of this link is secured by a pin 69 to an operating lever 70. The lever 70 may be housed in a casing 71 and is swingingly supported by a shaft 72 115 mounted in bearings 73. The lever 70 is positively rocked in one direction by an eccentric 74 upon a shaft 75 and this shaft may be driven by a pulley 76. The lever 70 preferably has a concaved surface 77 that rests against the eccentric 74 and partly embraces the eccentric, and the arrangement is such that as the eccentric rotates in the direction indicated by the arrow in Fig. 4 from the position shown in full lines, the lever 70 will follow the eccentric with an accelerated movement until the parts reach the position indicated at the right in dotted lines. At this position the eccentric engages the lower end 78 of the lever 70 and 125 130

quickly reverses its rocking movement. This reverses quickly the movement imparted to the deck, and as a result the momentum imparted to the materials causes them to slide along the deck. A spring 79 serves to hold the lever 70 in contact with the eccentric 74, and springs 80 connected to the arms 25 of the rocking frame 16 serve to rock this frame to move the deck 10 to the right as the eccentric 74 rotates away from the lever 70. Springs 81 connected to the brace 28 of the rocking frame 17 assist in imparting to the deck the movement just mentioned. The movement imparted to 15 the carriage and deck may be varied by connecting the link 67 with the lever 18 at different points by inserting the pin 68 in the different holes 82.

The movement imparted to the deck serves 20 to advance the materials lengthwise thereof, and their travel over the deck is promoted by the air passing upwardly through the deck, since the air lifts the particles and this enables them to move along the deck 25 more rapidly. The rate at which the materials travel over the deck will vary with the strength or volume of air used, and it is therefore desirable to increase the supply of air at the receiving end of the deck so 30 that the materials will be spread out rapidly over the width of the deck at this end. The volume of air is increased as desired by bending the lips 54 of the aperture 53 to vary the size of the openings, and since 35 air is introduced into the chamber at this end thereof the pressure will be somewhat greater at this end.

The riffles 52 preferably extend diagonally across the deck at an angle to the direction in which the materials are advanced 40 by the table movement, this arrangement causes the heavier materials to travel along the riffles toward the upper side of the deck. As the heavier materials deflected by the 45 riffles reach the ends thereof they meet the concentrate wall 82. This wall preferably is provided with the buffer blocks 83 which check the movement of the materials lengthwise of the wall and causes them to move 50 laterally of the deck over one or more riffles and travel along the same for further stratification.

In the present device the materials delivered to the deck will receive a preliminary 55 stratification as they spread out over the deck due to the disposition of the riffles and the action of the air. This will cause the lighter materials to move upwardly above the heavier materials whereupon they 60 will pass over the riffles and move laterally of the deck toward the lower side thereof. As the heavier particles or values travel along the riffles and pass from the end of one riffle to the next the materials will be 65 further classified and graded. This may be

continued until the values have traveled the entire length of the deck, or they may be drawn off at intervals as desired.

It is often desirable to direct the values discharged from the delivery end of the 70 deck into different receptacles and to this end a plurality of receptacles 84 are provided to receive these materials. The proportion of materials that enter any one receptacle may be varied by providing walls 75 85 pivoted at 86 between the receptacles, and adjustable as shown in dotted lines in Fig. 2 to vary the opening of a receptacle.

The lighter materials or tailings that pass over the riffles and move laterally of the 80 deck, due to its inclination, may escape through the openings 87 preferably closed by swinging doors 88. As the tailings pass through the openings 87 they slide along the inclined surface 89 (see Fig. 3) and 85 fall into a container 90. Canvas covers 91 and 92 preferably are provided extending from the deck casing to the container 90 to prevent the escape of dust. It is found undesirable to provide riffles at the 90 lower side of the deck casing 12 at the wide end thereof and an inclined plate 93 is therefore provided to exclude materials from this portion of the casing. The fan 95 may be driven by a belt 94 passing 95 around the pulley 95 upon the eccentric shaft 75.

It is found necessary to eliminate as far as possible any local vibrations that may be set up in the deck, as such vibrations 100 seriously interfere with the proper operation of the machine. A deck having its surface constructed entirely of riffles as in the present case will be free from local vibration and will operate in a highly efficient manner. The lips 54 preferably extend diagonally between the riffles 52 as shown and should direct the air currents toward the high side of the deck rather than 105 toward the low side.

A concentrator constructed in accordance 110 with the present invention is automatic in operation, requires but a minimum amount of attention, and is practically free from escaping dust.

What is claimed is:

1. A concentrator, comprising a deck having spaced transversely extending channel bars adapted to support the material supporting surface of the deck, and a composite deck surface upon said channel bars and formed of a multiplicity of apertured surface channels trough-shaped in cross section and mounted side by side upon the channel bars diagonally of the deck to form 120 a material supporting deck surface which will remain free from local vibrations during the operation of the deck.

2. A concentrator, comprising a deck having spaced transversely extending channel 125

- bars adapted to support the material supporting surface of the deck, and a composite deck surface upon said bars and formed of a multiplicity of apertured surface channels trough-shaped in cross-section and secured side by side upon the channel bars to form a material supporting deck surface which will remain free from local vibrations during the operation of the deck.
3. A concentrator, comprising a deck having spaced transversely extending channel bars adapted to support the material supporting surface of the deck, a composite deck surface upon said bars and formed of a multiplicity of apertured surface channels trough-shaped in cross-section and secured side by side upon the channel bars to form a material supporting deck surface which will remain free from local vibrations during the operation of the deck, and spaced partitions extending longitudinally of the deck below the channel bars to support these bars and adapted to form longitudinally extending air chambers below the deck surface.
4. A concentrator, comprising a deck having spaced channel bars for supporting the material carrying surface of the deck, a composite deck surface upon said bars and formed of a multiplicity of apertured surface channels trough-shaped in cross-section and secured side by side upon the channel bars to form a material supporting surface which will remain free from local vibrations during the operation of the deck, and an inclined lip at each aperture to direct air passing therethrough.
5. A concentrator comprising a deck having spaced channel bars for supporting the material carrying surface of the deck, a composite deck surface upon said bars and formed of a multiplicity of apertured surface channels trough-shaped in cross-section and secured side by side upon the channel bars to form a material supporting surface which will remain free from local vibrations during the operation of the deck, and inclined lips at the apertures to deflect materials from the apertures.
6. A concentrator table comprising, in combination, a supporting frame having a deck mounted thereupon for movement back and forth, means for supporting the deck at a transverse inclination, means for delivering materials to be treated to the deck, ripples extending diagonally across the deck toward the upper side thereof, a cover for said deck having openings along the lower side of the deck for the discharge of lighter materials, means for actuating the deck to move the materials longitudinally thereof, and a flexible cover extending over said discharge openings to prevent the escape of dust.
7. A concentrator table comprising, in combination, a deck, means for imparting movement to the deck to advance materials longitudinally thereof, means for passing air upwardly through the deck, ripples extending over the deck surface, a cover for said deck having perforations formed through a substantial portion thereof, and a hood mounted upon the cover over said perforations to form a chamber for receiving air from the space between the deck and cover and for delivering the air to a conduit.
8. A concentrator table comprising, in combination, a supporting frame, rocking arms pivotally mounted upon the frame to swing in a vertical plane, a concentrating deck supported by said arms, an operating lever having a concave surface and connected to one pair of said arms to rock them and thereby impart movement to the deck, and an eccentric mounted to rotate in contact with the concave surface of the lever and thereby actuate the latter to impart a movement to the deck that is more rapid in one direction than in the other.
9. A concentrator table comprising, in combination, an elongated deck casing having a perforated deck surface therein and an air chamber below the deck surface, means for imparting movement to the deck casing to promote movement of the materials being treated along the deck, spaced partitions below the deck surface and extending longitudinally within said air chamber to divide it into separate longitudinally extending compartments and adapted to support said deck surface and to prevent the air below the deck from flowing laterally from one portion of the deck to another.
10. A concentrator table comprising, in combination, a supporting frame, a deck supported by the frame for movement back and forth in the direction of its length, and means for imparting a rapid vibratory movement to the deck which is more energetic in one direction than the other to promote stratification of the materials and advance them along the deck, including, a rocking arm supported by the frame and connected to the deck, a rotating shaft having an eccentric that is supported and rotated by the shaft, an operating lever pivotally mounted near the eccentric and having a concaved surface that engages and partly embraces the eccentric so that the eccentric moves along the concave surface relative to the lever pivot as it rotates to vary the movement imparted to the lever, and a connection between said lever and arm to impart the movement of the lever to the deck and move the latter more rapidly in one direction than the other.
11. A concentrator table comprising, in combination, a supporting frame, a deck supported by the frame for movement back and forth in the direction of its length, and means for imparting a rapid vibratory

- movement to the deck which is more energetic in one direction than the other to promote stratification of the materials and advance them along the deck, including a 5 rotating shaft having an eccentric that is supported and rotated by the shaft, an operating lever pivotally mounted near the eccentric and having a concave surface that engages and partly embraces the eccentric 10 so that the eccentric moves along the concave surface to act upon the same at different distances from the lever pivot to vary the movement of the lever, and a connection between the lever and deck to move the deck 15 more rapidly in one direction than the other.
12. A concentrator table comprising, in combination, a supporting frame, rocking levers connected by transversely extending bars to form strong rocking frames for 20 supporting a deck, a shaft for pivotally securing an intermediate portion of a rocking frame to the supporting frame, a deck sup-
- ported by the portion of the rocking frame above said shaft, and means connected to the lower end of one of said frames to rock 25 it and impart a vibratory movement to the deck which is more energetic in one direction than the other to promote stratification of the materials and advance them along the deck, including a rotating shaft having an eccentric that is supported and rotated by the shaft, an operating lever connected to said rocking frame and pivotally mounted near the eccentric and having a surface that engages the eccentric and along which the 30 eccentric moves as it rotates to act upon the lever at different distances from the lever pivot to vary the movement of the lever and move the deck more rapidly in one direction than the other.
- 40 In testimony whereof, I have signed my name to this specification.

ALBERT H. STEBBINS.
